UNITED STATES PATENT OFFICE.

CHARLS F. SMITH, OF HAYNESVILLE, LOUISIANA.

WELL-CLEANER.

999,603.

Specification of Letters Patent. Patented Aug. 1, 1911.

Application filed October 28, 1909. Serial No. 525,121.

To all whom it may concern:

Be it known that I, CHARLS F. SMITH, a citizen of the United States, residing at Haynesville, in the parish of Claiborne, 5 State of Louisiana, have invented certain new and useful Improvements in Well-Cleaners; and I do hereby declare the following to be a full, clear, and exact description of the invention, such as will enable others skilled in the art to which it appertains to 10 make and use the same.

This invention relates to improvements in well cleaners and has for its object the provision of a device of that kind provided with 15 a pair of scoops arranged to be inserted into a well and when so inserted to tilt upwardly when coming into engagement with the bottom of the well so that the dirt or other matter thereon will be removed 20 from the well.

One object of the invention is the provision of a means for tripping or folding the scoops after the same engage with the bottom of the well.

Another object is the provision of a 25 means for adjusting the tripping mechanism so that when soft mud or the like is to be taken from the well the scoops will not close until they have penetrated the soft 30 mud for a considerable distance.

With the above and other objects in view as will more fully hereinafter appear, the present invention consists in certain novel details of construction and arrangement of 35 parts, hereinafter fully described, illustrated in the accompanying drawings and more particularly pointed out in the appended claims; it being understood that various changes in the form, proportion, size and 40 minor details of the device may be made without departing from the spirit or sacrificing any of the advantages of the invention.

In the accompanying drawings forming 45 part of the specification:—Figure 1 is a vertical sectional view of a well and showing my improved device in elevation and inserted into the well; Fig. 2 is a front elevation of the device showing the scoops in 50 folded or engaging position. Fig. 3 is a sectional plan view approximately on the line 3—3 of Fig. 1. Fig. 4 is a vertical sectional view on the line 4—4 of Fig. 1.

Similar numerals of reference are employed to designate corresponding parts 55 throughout.

The device consists essentially in a pair of operating arms designated by the numerals 5 and 6. These members may be of any preferred length and what will subsequently be termed their upper end portions are curved, the extremities of said curved portions being pivoted together by a pivot pin 7. Pivoted to the opposite or lower ends of the arms 5 and 6 are the outer ends of a pair 60 of links 8 and 9. The links 8 and 9 are arranged on opposite sides of the arms 5 and 6 and located between the inner ends of the links is the upper end of what will subsequently be termed a tripper. This member 70 is preferably formed of an oblong piece of sheet metal corresponding in thickness to the thickness of the arms 5 and 6 and its upper or connected end portion is provided with an opening adapted to align with similar openings formed in the inner ends of the links 8 and 9, the said alining openings receiving a pivot pin 10, by means of which the links are pivoted together and united to the tripper. It might here be stated, 75 when the links are at right-angles to the straight portions of the arms 8 and 9 their combined lengths will be sufficient to hold the straight portions of said arms, parallel.

The upper or connected end portion of 85 the tripper is designated by the numeral 11 and is oblong but of considerably less length than the lengths of the links. The opposite ends of the oblong head extend for equal distances on either side of the pivot pin 10, 90 and the upper edge of this head is provided adjacent the opposite ends with a pair of oppositely extending lugs 12 and 13, which are on opposite sides of the pivot pin 10. The function of these lugs is to limit the 95 outward movement of the links 8 and 9 since it can be readily seen when the said links 8 and 9 are at right angles to the straight portions of the arms 5 and 6 as shown in Figs. 1 and 3 that further outward 100 movement of the links will be prevented by virtue of the lugs 12 and 13 bearing on the upper sides of said links. The lower side of the oblong head 11 terminates in an elongated shank 14, provided with a longitudinal slot 15. A foot is provided for the shank 105

and consists of a flat base or bearing surface 16, from the intermediate portion of which rise a pair of spaced sides 17 and 18. The distance between the sides 17 and 18 5 corresponds approximately to the thickness of the shank 14 and extending through alining openings in the upper ends of the sides is a bolt 19.

By referring now to Fig. 4 it will be seen 10 that when the parts are in position the bolt 19 will extend through the slot 15 and it will be further observed that by tightening the nut 20 on the threaded end of the bolt the foot will be clamped to the shank. With 15 this construction it is evident that the tripper is extensible, that is to say, that by clamping the foot to different points on the shank 14 the scoops to be presently described will close after they have penetrated 20 the soft mud on the bottom of the well, at various distances.

The scoops are designated by the numerals 21 and 22 and are preferably formed of single pieces of sheet metal or the like 25 bent into the shape of semi-circles. The scoops are closed at one end by walls 23 and formed integral with the outer face of the walls 23 are ribs 24. These ribs 24 extend transverse the walls and are located to 30 one side of the centers of the same. The end edges of the scoops opposite the ends provided with walls 23 incline inwardly as shown at 25 and the combined lengths of the scoops are somewhat less than the combined lengths of the links 8 and 9 so that 35 when the scoops are folded as shown in Fig. 2 the inclined edges of the scoops will bear one upon the other. The ribs 24 are provided with a plurality of openings which 40 are adapted to aline with a plurality of similar openings formed adjacent the ends of the links, these alining openings receiving suitable bolts or screws 26 and by means of the scoops are secured to the links as shown 45 in Fig. 4 and through the final opening of the series of openings are engaged suitable bolts or screws 26, by means of which the arms 5 and 6 are pivotally connected to the links, thus pivotally connecting the scoops 50 to the arms as clearly shown in Fig. 2. The inclined edges of the scoops are provided with a plurality of outwardly curved interlocking teeth 27, these teeth being so positioned that the closing movement of the 55 scoops which bring their inclined edges to bear one upon the other will not be prevented.

In the operation of the device the arms 5 and 6 are spread apart until the links 8 60 and 9 are at right angles to the straight portions of the arms 5 and 6. When the parts are so positioned the scoops 21 and 22 will extend vertically downward from the links 8 and 9 and the tripper will be 65 located between the said scoops. The device

is now ready to be lowered into the well to be cleaned and in order that the device may be readily handled and withdrawn from the well a cord or cable 28 is employed and has one end secured in a clevis 29 at 70 the connected ends of the arms and by means of the cord or cable 28 the device is now lowered until the tripper bears on the bottom of the well. When extremely soft mud is to be taken up it is evident that the tripper will penetrate the said mud to a considerable distance before coming into contact with the hard surface of the bottom. When the passage of the tripper is thus impeded it is evident that the weight of the device 75 now on the tripper will cause the latter to move upwardly relative to the downward movement of the arms 5 and 6, whereby the inner connected ends of the links will move upward and at the same time the scoops will move toward each other and fold as shown in Fig. 2, this folding movement of the scoops lifting and forcing into the scoops all the material in the space between their opposed inner faces. The closing movement 80 of the arms and scoops may be augmented by means of a retractile spring 30, the opposite ends of which are secured to the upper end portions of the arms 5 and 6 so that when the tripper moves upwardly as before 95 described, the action of this spring will draw the arms toward each other as shown in Fig. 2.

What is claimed as new, is:—

1. A well cleaner comprising a pair of 100 pivoted arms, a pair of links having their inner ends pivotally united and their outer ends pivoted to said arms and serving to move the latter relatively to each other, scoops carried by said links and normally held closed, a ground contacting tripper connected to said links serving to impart closing movement to the latter, and oppositely extending lugs carried by said tripper 105 engaging said links and limiting the opening movement of said links.

2. A well cleaner comprising a pair of 110 spring controlled pivoted arms, a pair of links pivotally united adjacent to their inner ends and having their outer ends pivoted to said arms and serving to move the latter relatively to each other, scoops carried 115 by said links and normally held closed, an extensible ground engaging tripper pivotally connected to said links and serving to impart closing movement thereto, and oppositely extending lugs carried by the tripper and engaging the links, whereby to limit the opening movement of said links.

3. A well cleaner comprising a pair of 120 pivoted arms, a pair of links having their inner ends pivotally united and their outer ends pivoted to said arms and serving to move the latter relatively to each other, 125 scoops carried on the outer ends of said 130

links, an extensible ground contacting tripper arranged between said scoops and pivotally connected with said links by a single pivot pin common to the links and tripper, 5 said tripper serving to impart closing movement to the links, said tripper having a head portion formed with oppositely projecting lugs on opposite sides of its pivot,

engageable with said links, whereby to limit the opening movement of the links.

In testimony whereof, I affix my signature, in presence of two witnesses.

CHARLS F. SMITH.
